PULP WOOD RECLAIMER

Keith O. Guthrie, Pleasantville, N. Y.

Application January 10, 1931, Serial No. 507,910

Renewed January 12, 1934

15 Claims. (Cl. 198—171)

This invention relates to pulp wood reclaimers.

In the manufacture of wood pulp, the wood which is to be converted into pulp, consisting of pieces of about four-foot length and varying from 5 to ten inches in diameter, is concentrated at the mills, sometimes covering an area of several acres. It lies in large pyramidal piles and from these piles it is transported to the chipping, shredding, or grinding plant where it undergoes 10 the first stage of its preparation into commercial pulp. This transportation is usually accomplished by endless conveyors, commonly referred to as reclaimers. These customarily have a series of vertical flights, carried by a continuously moving cable, chain or belt, travelling within a longitudinally extending trough in which the wood is deposited. In practice three different modes of employing these reclaimers ordinarily prevail: The conveyor trough may be disposed upon the 15 surface of the ground in parallelism with the side of the pile being reclaimed; it may be contained in a ditch extending beneath the base of the pile; or it may be enclosed in a specially constructed tunnel penetrating the pile. In the latter two 20 cases the top of the ditch or the roof of the tunnel is formed of corded timber which may be removed in sections. The wood is charged into the conveyor trough by a gang of workmen especially employed for that purpose and, where either of 25 the last two arrangements is employed, sections of the corded timber are removed from time to time to keep pace with the receding edge of the pile.

It is an object of the present invention to provide 30 a reclaimer which dispenses with the large amount of manual labor heretofore required and with the excavating of ditches or constructing of tunnels, while at the same time maintaining a continuous and substantially automatic feed of pulp wood to the plant. This object is attained 35 in the reclaimer of the invention by providing a series of flights slideable along an elongated flat runway disposed near the base of the pile of wood, with the ends of the flights projected beyond the 40 runway and so shaped as to plow under and unbalance the wood and cause it to tumble down upon the runway into the path of the flights where it is pushed, by abutments preferably constituting a portion of the flights, to a point of 45 discharge; and in the preferred embodiment of the invention this action of the flights on the bottom of the pile is facilitated by so shaping the projected ends of the flights as to impart a series of vertical impulses to the wood. As the edge of the 50 pile is eaten away the reclaimer is adapted to be

60 moved closer to the pile so that the flights obtain a new bite in the bottom of the pile; but in order that the necessity for relocating the reclaimer may be reduced to a minimum, it is so constructed that the flights may be readily adjusted different distances toward the pile by the manipulation of a hand lever without either disturbing the original position of the reclaimer or arresting its 65 operation.

The invention will be better understood from 65 the description which follows of a preferred embodiment, reference being had to the accompanying drawings in which

Fig. 1 is a perspective view of the reclaimer;

Fig. 2 is a perspective view of a novel form 70 of flight, and

Fig. 3 is an enlarged cross-sectional view taken on the line 3—3 of Fig. 1 indicating the mode of attachment of the flight to the flexible cable of the reclaimer.

As shown in Fig. 1 the reclaimer consists of 75 a pair of sheaves 1 and 2 lying in a common horizontal plane an appropriate distance apart, and connected by an endless cable 3 to which is attached a series of flights 4. The flights are 80 constituted of flat metal plates and extend in a direction away from the area enclosed by the cable. The sheaves 1 and 2 are journaled respectively upon a pair of vertical stud shafts 7 and 8 mounted at opposite ends of a base plate 85 5 which is designed to rest flatly upon the ground adjacent the pile of pulp wood to be reclaimed. The sheaves are each circumferentially provided with a groove 6 to receive the cable and guide it thereover. For imparting movement to the cable 90 in the direction indicated by the arrows in Fig. 1, an electric motor 9, mounted on one end of the base plate, drives the sheave 1 through a bevel gear 10. The bevel gear is carried upon a counter-shaft 11, and meshes with a bevel ring gear 12 concentrically fastened upon this sheave. Suitable speed-reduction mechanism, housed within a gear box 13, is interposed between the armature shaft of the motor and the countershaft in order that the cable may be 95 driven at an appropriate speed.

Skirting that side of the base plate, 5 which is disposed nearest the pile of wood, is an apron 14 of substantial width. This apron, following the direction of the outer run of the cable 3 105 and having a smooth wear-resistant surface, defines a runway along which is adapted to slide a series of conveyor blocks 15 fastened upon the cable. Each conveyor block 15 is composed of two superposed sections 16 and 17, as shown 110

in Fig. 3, having complementary grooves 18 and 18a, which together form an opening for receiving the cable 3. The inner end 19 of the flat metal plate composing the flight 4 is generally 5 U-shaped in horizontal cross-section and serves to box the lower surface of the section 17, the rear face of this section being cut away as indicated at 20 to cause the upwardly bent end of the flight to lie flush with the rear wall of 10 the conveyor block 15. The two sections 16 and 17 are held in clamping engagement with the cable 3, and the flight 4 is maintained in rigid assembly with the conveyor block 15, by means of bolts 21 countersunk within the bottom face 15 of flight 4 and extending vertically up through apertures formed in sections 16 and 17. It will be apparent that the flat vertical legs of the box portion of the flights embrace the front and rear walls of conveyor blocks 15 and afford means to 20 effectively resist twisting of the flights in a horizontal plane.

The conveyor blocks 15 in operation slide along the apron, covering only a portion of its width. In order that these blocks may pass smoothly 25 around the sheaves 1 and 2, the sheaves are each provided with circumferentially spaced notches 22. These notches are designed to receive the blocks as the cable winds over the sheaves but they serve the additional function of preventing 30 the cable from slipping.

The metal plates constituting the body portions of the flights 4 are each of such form as to define three distinct areas, namely, a U-shaped box portion 19 embracing the lower portion of 35 the conveyor block 15 which has already been described, an intermediate bridging portion 23 leading from the box portion and spanning the apron 14 a short distance above its surface, and a flat terminal portion 24 lying at a suitable 40 distance beyond the outer edge of the apron. By such construction the bridging portions 23, acting in conjunction with the conveyor blocks 15, serve to clear the runway of material deposited thereon. The flat terminal portion is 45 vertically offset with respect to the bridging portion, with which it is connected through a bend 24', so as to lie at an elevation slightly above the level of the ground. Upon the terminal portion 24 of the flight is rigidly fixed, as by welding, a wing plate 25 disposed crosswise of the flight. This wing plate may be said to lie generally in a flat horizontal plane, but being formed intermediate its length with a fold defining a small hump 26 which arches over the bend 24' 50 of the flight. By reason of this fold, the inner edge of the wing plate is contracted so that the wing plate assumes in plan view a slightly arcuate form. The inner marginal portion of the wing plate upon opposite sides of the terminal portion 24 of the flight is bent slightly upwardly 55 so as to overlap the edge of the apron 14 as shown in Figure 3. When the reclaimer is operated, therefore, the wing plate plows under the entangled pieces of pulp wood at the edge 60 of the pile while the hump 26 imparts a gentle lifting and falling motion to dislodge the wood and cause it to avalanche down upon the apron in the path of the flights.

The mechanism by which the series of flights 70 is readily adjustable outwardly so as to obtain a deeper bite in the side of the pile will now be described.

The inner sides of the conveyor blocks 15 in their movement are arranged to rub against the 75 vertical wall of an angle iron 27 of inverted L-

section, and this angle iron in turn is slidable toward and away from the edge of the apron 14. Rigidly fastened upon the opposite side of the angle iron and directed inwardly with respect to the area embraced by the cable 3, are 80 a number of shift rods 28 and each of these rods is pivotally connected to the free end of a toggle 29. The fixed end of the toggle is pivoted on a pin 30 extending vertically from the face of base plate 5 and the series of toggles 85 is arranged to be operated by a pull bar 33 disposed longitudinally of the base plate and pivotally connected to each of the toggles 29. A hand lever 34, fastened at one end of the base plate, where it is readily accessible to the operator, and arranged to swing in a vertical plane, is connected to the pull bar 33 so that when the lever is moved in one direction the toggles are simultaneously expanded and a 90 thrust is imparted to the shift rods 28. The hand lever may be maintained in different positions of adjustment by means of a pawl and ratchet mechanism 34'. This forces the angle iron 27 against the conveyor blocks 15 to move 95 the cable 3, together with the flights 4, closer to the pile of wood. This slight expansion of the relatively long cable is permitted by reason of the slack which normally exists therein. The two ends of angle iron 27 are fastened by pin and slot connections 35 to a vertical plate 36, 100 and the plate 36 is formed with a suitable number of oversize openings through which pass the shift rods 28. Accordingly, when the angle iron is slid outwardly, its ends, being held against outward movement, will be bowed to define 105 ramps for leading the conveyor blocks to and from the forwardly projected section of the angle iron. The horizontal flange of the angle iron 27 overhangs the conveyor blocks 15 so as to maintain them against vertical displacement 110 on the runway and to prevent material from jamming between the conveyor blocks and the vertical wall of the angle iron. This flange is slit near its ends, as shown at 37, in order that bending may more readily occur. A spring 38 interposed between the pull bar 33 and the hand 115 lever 34 allows the angle iron 27 to yield when the flights strike an immovable obstruction.

The reclaimer is provided with a gable roof 40 of stout planks running lengthwise of the apparatus and supported at spaced intervals 120 upon angular frames 41. These frames have upright legs 42 terminally toed in toward each other to permit attachment to the base plate 5. The plate 36 is fastened to the vertical legs 42 125 of the frames so as to constitute a wall with which the angle plate 27 contacts when the latter is in fully retracted position. The plate 36 has a horizontally disposed overhanging flange 43 which affords a shoulder against which the edge of the timber composing the lower end of 130 the roof may rest and thus be reinforced against injury by the wood as it tumbles down upon the conveyor.

At the delivery end of the reclaimer, the apron 44 may be cut away to define a clearance opening 135 in the path of the flights in which another conveyor may be stationed for transporting the wood to a more remote point of discharge. A small winch 45, manually operable, comprising a drum upon which is wound a cable having one 140 end anchored, for example, to a "dead man" buried in the ground, may be mounted at each end of the base plate to afford ready means for shifting the apparatus over the ground.

In operation, the reclaimer is drawn up along 145

side the pile of pulp wood so that the apron 14 will skirt the bottom of the pile. The motor 9 is started which, through gears 10 and 12, imparts rotation to the sheave 1. This draws the cable 5 3 thereover, the conveyor blocks 15 on the cable sliding along the flat runway defined by the apron and engaging within the correspondingly shaped notches 22 in the sheaves 1 and 2 as the cable winds thereover. The flights 4, being 10 rigidly fastened to the cable and having their outer ends extending a substantial distance beyond the margin of the apron 14, pass under the entangled pulp wood at the bottom of the pile with a plow-like action. The humps 26 15 upon the wing plates 25 at the flat ends of the flights serve to impart a series of alternate lifting and sinking impulses to the wood so as to unsettle and tickle it down upon the apron where it is caught up by the conveyor blocks 15 and 20 the bridge portions 23 of the flights and swept along the runway to a point of discharge near the end of the reclaimer. Pieces of wood falling upon the sloping roof 40 of the reclaimer slide down upon the runway and are similarly 25 disposed of. As convenience may dictate, the reclaimer may feed directly into a hopper located at the plant or it may deliver to another conveyor which in turn transports the wood to the mill.

30 As the side of the pile is eaten away and the effectiveness of the reclaimer decreases, the ends of the flights may, without interrupting the operation of the machine, be projected further into the pile by operating the hand lever 34. Operation of this lever through the action of toggles 29 shifts the angle plate 27 outwardly which, pressing against the conveyor blocks 15, takes up slack in the cable and moves it, together with the flights 4, closer to the pile. Eventually, however, 40 the flights will have attained their extreme position of adjustment and the entire reclaimer must then be relocated nearer to the pile. When this is the case it may be shifted either bodily or in an arc by operating either one or both of the 45 winches 45 mounted upon the ends of the reclaimer.

Under certain conditions it may be desirable to afford support for an intermediate portion of the flights and this may be done by providing a 50 bead upon the outer edge of the apron 14 of a height requisite to engage under the bridge of the flights. This bead will also serve a secondary purpose of preventing pieces of wood from rolling off the runway during operation.

55 Furthermore, it is not necessary that the apron 14 be rigidly connected to the base plate 5, but in order to accommodate itself to irregularities on the ground, it may be longitudinally hinged to the side of the base plate and form what may be 60 termed a floating runway for the series of flights.

I claim:

1. A pulp wood reclaimer comprising an approximately horizontally disposed flexible member adapted to be positioned adjacent a pile of wood, means for driving the flexible member, and a plurality of laterally extending flights spaced along the flexible member and connected therewith, said flights having their ends lying generally in a horizontal plane and having a slightly 65 projecting surface upon said ends so as to plow under the entangled pulp wood at the edge of the pile and impart a series of vertical impulses thereto.

2. A pulp wood reclaimer comprising an approximately horizontally disposed flexible mem-

ber adapted to be positioned adjacent a pile of wood, means for driving the flexible member, and a plurality of laterally extending flights spaced along the flexible member, said flights having their ends lying generally in a horizontal plane and having a hump upon said ends so as to plow under the entangled pulp wood at the edge of the pile and impart a series of vertical impulses to the wood, and an abutment carried by the cable for engaging behind and conveying away the 80 wood disintegrated by said impulses and falling in the path of travel of the abutments.

3. A pulp wood reclaimer comprising an approximately horizontally disposed flexible member adapted to be positioned adjacent a pile of wood, a runway located in a plane below the flexible member, means for driving the flexible member, and a plurality of laterally extending flights spaced along the flexible member and having their ends projecting beyond the outer edge of the runway and lying generally in a horizontal plane to plow under the entangled pulp wood at the edge of the pile, said ends having a hump thereon to impart a series of vertical impulses to the wood.

4. A pulp wood reclaimer comprising an approximately horizontally disposed flexible member adapted to be positioned adjacent a pile of wood, means for driving the flexible member, a runway, located in a plane below the flexible member, a plurality of flights spaced along the 105 flexible member and having their ends projecting beyond the outer edge of the runway and lying generally in a horizontal plane to plow under the entangled pulp wood at the edge of the pile, said ends having a hump for imparting a series of vertical impulses to the wood, and a plurality of abutments carried by the flexible member adapted to engage the wood falling upon the runway.

5. A pulp wood reclaimer comprising an approximately horizontally disposed flexible member adapted to be positioned adjacent a pile of wood, means for driving the flexible member, a runway located in a plane below the flexible member, a plurality of flights fastened to the flexible member at spaced intervals and projecting beyond the outer edge of the runway, the terminal portions of said flights lying generally in a horizontal plane to plow under the entangled pulp wood at the edge of the pile and having a hump for imparting a series of vertical impulses to the 115 wood, a plurality of abutments carried by the flexible member adapted to engage the wood falling upon the runway, and means for extending the flights to a position nearer the pile without disturbing the location of the reclaimer.

6. A pulp wood reclaimer comprising an approximately horizontally disposed flexible member adapted to be positioned adjacent a pile of wood, means for driving the flexible member, a flat runway located in a plane below the flexible 135 member, a plurality of flights fastened to the flexible member at spaced intervals and projecting beyond the outer edge of the runway, said flights having their terminal portions lying generally in a horizontal plane to plow under the entangled pulp wood at the edge of the pile and having a hump for imparting a series of vertical impulses thereto, a plurality of abutments each constituting a portion of a flight adapted to engage the wood falling upon the runway, and 140 means for moving the flexible member closer to the pile of wood without disturbing the location of the reclaimer.

7. A pulp wood reclaimer comprising an approximately horizontally disposed flexible mem-

- ber adapted to be positioned adjacent a pile of wood, means for driving the flexible member, a flat runway located in a plane below the flexible member, a plurality of conveyor blocks carried by the flexible member and adapted to slide along the runway, a plurality of flights fastened to the conveyor blocks and projecting beyond the outer edge of the runway, said flights consisting of a terminal portion lying generally in a horizontal plane to plow under the entangled pulp wood at the edge of the pile and having a hump for imparting a series of vertical impulses to the wood and an intermediate portion bridging the runway at a slight distance thereabove, and means for moving the flexible member closer to the pile of wood without disturbing the location of the conveyor, said means comprising a movable plate adapted to shift the flexible member outwardly toward the pile.
- 20 8. A pulp wood reclaimer comprising an approximately horizontally disposed endless cable adapted to be positioned adjacent a pile of wood, a flat runway located in a plane below the cable, sheaves over which the cable is trained for driving the cable, a plurality of flights fastened to the cable and projecting beyond the outer edge of the runway, said flights having their terminal portion lying generally in a horizontal plane and having a hump to plow under the entangled pulp wood at the edge of the pile to impart a series of vertical impulses thereto, and a plurality of conveyor blocks carried by the cable adapted to engage the wood falling upon the runway, and manually operable means for shifting a run of the cable to a position nearer the pile.
- 30 9. A pulp wood reclaimer comprising an approximately horizontally disposed cable adapted to be positioned adjacent a pile of wood, a flat runway located in a plane below the cable, sheaves over which the cable is trained for driving the cable, a plurality of flights fastened to the cable and projecting beyond the outer edge of the runway, said flights having their terminal portion lying generally in a horizontal plane and having a hump to plow under the entangled pulp wood at the edge of the pile and impart a series of vertical impulses thereto, a plurality of conveyor blocks carried by the cable adapted to engage the wood falling upon the runway and manually operable means for extending the flights to a position nearer the pile, said means comprising a slide-able plate adapted to engage the conveyor blocks upon the flexible member and toggles for sliding the plate outwardly.
- 40 10. A flight for use in a pulp wood reclaimer having an intermediate portion and a terminal plow portion extending longitudinally in the direction of movement of the flight and lying generally in a horizontal plane, said terminal portion being provided with a hump whereby the terminal portion is adapted to plow under the entangled pulp wood at the edge of the pile and impart a series of vertical impulses thereto to unsettle the wood and cause it to tumble upon the reclaimer.
- 50 11. A pulp wood reclaimer comprising an elongated runway adapted to have a longitudinal edge thereof positioned alongside of a pile of wood, a plurality of spaced members for unsettling the wood which are disposed in a direction lateral to said runway and extend beyond said edge substantially through the length thereof whereby their ends will project into the pile of wood when said runway is disposed with the longitudinal edge alongside of the pile, and means for moving said members longitudinally of said runway to cause said members to impart a series of vertical impulses to the wood.
- 60 12. A pulp wood reclaimer comprising an elongated runway adapted to have a longitudinal edge thereof positioned adjacent a pile of wood, a plurality of spaced members for unsettling the wood which are disposed in a direction lateral to said runway and extend beyond said edge whereby their ends may be caused to project into the pile of wood, said ends being provided with an undulated member disposed with the undulation longitudinally of said runway, and means for moving said members longitudinally of said runway.
- 70 13. A pulp wood reclaimer comprising a runway adapted to be positioned adjacent a pile of wood, a plurality of spaced members disposed laterally of said runway in the direction of the pile, means for moving said members in said runway, and means for extending the members nearer the pile without disturbing the location of the reclaimer.
- 80 14. A pulp wood reclaimer comprising an elongated runway adapted to have a longitudinal edge thereof positioned adjacent a pile of wood, a plurality of spaced members for unsettling the wood which are disposed in a direction lateral to said runway and extending beyond said edge whereby their ends may be caused to project into the pile of wood, means for moving said members longitudinally of said runway, and means for extending the members nearer the pile without disturbing the location of the reclaimer.
- 90 15. A pulp wood reclaimer comprising an elongated runway adapted to have a longitudinal edge thereof positioned adjacent a pile of wood, a plurality of spaced members for unsettling the wood which are disposed in a direction lateral to said runway and extend beyond said edge whereby their ends having a hump thereon to impart a series of vertical impulses to the wood means for moving said members longitudinally of said runway, and means for conveying along said runway the wood discharged thereupon from said pile.
